UNITED STATES PATENT OFFICE.

CHARLES D. WALDON, SAMUEL J. BROOKS, AND ROBERT T. ROBINSON, OF TORONTO,
ONTARIO, CANADA.

HEATER.

Application filed September 21, 1927, Serial No. 220,956, and in Canada November 15, 1926.

This invention relates to a heater of the type of self-feeding magazine heaters which are provided with a water cooled hopper. Our object is to devise a hopper which is 5 of simple construction and which is adapted to allow manual stoking of the heater as well as the automatic feeding, or which may be easily removed so as to eliminate the self-feeder when it is desired to use fuel 10 which is not adapted for use in the heater when the self-feeder is in position.

We attain our object by constructing the hopper with inclined sides and one inclined end of peculiar construction as herinafter 15 described, and by securing it to the heater by means of connections which are easily removable.

The construction of our device is herein- 20 after more fully described and illustrated in the accompanying drawings in which

Fig. 1 is a front elevation of the heater, partly broken away and partly in section; and

Fig. 2 is a longitudinal section of the 25 heater, partly broken away.

In the drawings like numerals of reference indicate corresponding parts in the different figures.

The heater consists of a casing 1 and a 30 front water header 2 and a rear water header 2^a. At the top of the heater are steam and water drums 7 opening into the front and rear headers and pipes 4 also extend between and communicate with the headers. Carried in the pipes 4 and spaced therefrom are flues 4^a which pass through the headers 2 and 2^a to front and rear smoke boxes 3 and 3^a respectively. The smoke boxes 3 and 3^a are provided with removable covers. Thimbles 40 pass through the front header 2 and provide a means of communication between the interior of the heater and the front smoke box 3.

The heater is provided with grates 5 which 45 are preferably of inverted V-shape with the apex running from front to rear in the middle of the heater. When the heater is in operation the smoke and hot gases pass from the burning fuel between the pipes 4 and 50 thence through the thimbles 6 to the smoke box 3. From thence the smoke passes through the flues 4^a to the smoke box 3^a, and from thence to a chimney which communicates with the smoke box 3^a, and is not 55 shown.

So far the construction and operation is that of the ordinary well-known type of heater.

At the front of the header is a fuel opening 8 passing through the smoke box 3 and the header 2, and being provided with a door. Above the grates 5 is a fuel magazine and feeder, the sides of which are formed by the pipes 4 and which includes at its lower end a hopper 10 with inclined sides 60 10^a and an inclined end 10^b. The sides and end are of hollow construction and adapted to hold water. The interiors of the sides and end communicate freely with one another. One end of the hopper is closed 65 by the rear header 2^a. The other end 10^b is adjacent the front of the header and is inclined rearwardly so that the fuel will be fed towards the centre of the grate and for the purpose herinafter described. 70

Below the fuel opening 8 is an opening 9 which passes through the header 2 and the smoke box 3, and is provided with a door. When it is desired to use fuel such as wood 75 slabs or large coal that will not pass through the hopper, such fuels may be manually fed to the heater through this door. The inclination of the hopper end 10^b gives room between the hopper end and the grates at the forward end for the insertion of such fuel. 80

The hopper end 10^b is cut away at the bottom to a predetermined extent (as shown at 10^c) so that the fuel flowing out of the hopper and assuming its natural angle of repose would reach the outer end of the 85 grates.

The front of the hopper is secured by means of a saddle or bent bar 11 to the header 2. This saddle is secured to the bottom of the fuel opening 8 and to the hopper end 10^b, by bolts 21. In order to provide circulation of the water in the interior of the sides and end of the hopper, pipe connections are provided which communicate with the steam and water drums 7 and the header 90 2^a. The interior of the sides and end of the hopper communicates with the interior of the steam and water drums by means of pipes 12 provided with unions 13 which are accessible through the fuel opening. These 95 pipes 12 are screwed into the sides 10^a of the hopper near the top of the hopper and at the front thereof. Near the bottom of the hopper and at the rear thereof a pipe 14 communicates with the interior of each side 100 105 110

10^a of the hopper. This pipe 14 is screwed into the side 10^a and passes through a thimble 20, which is formed in the header 2^a to the smoke box 3^a where it is joined to 5 the pipe 16 by means of the elbow 15. In the pipe 16 is a union 17. The pipe 16 is connected to the pipe 19 by means of an elbow 18, and the pipe 19 is screwed into the header 2^a and communicates with the interior thereof.

When it is desired to use large fuel such as logs the self-feed arrangement is dispensed with and the connections described above make it possible to easily remove the 15 hopper for this purpose. To do this the unions 13 are unscrewed and the bolts 21 are removed. The cover of the rear smoke box 3^a is removed and the unions 17 are unscrewed. The pipe 14 is then screwed out 20 of the wall 10^a of the hopper. This leaves the hopper free and it drops to a position opposite the opening 9 through which it is easily removed.

What we claim is:

25 1. A magazine heater having a casing; front and rear headers; a fuel magazine within the casing and extending between the headers; a water jacketed hopper extending between the headers beneath the 30 said magazine; water receiving means above the magazine; detachable connections between the interior of the upper part of the jacket of the hopper and the interior of said means; detachable connections between the 35 interior of the lower part of the jacket and the interior of a header; and an opening through the casing and front header, the hopper having one end thereof adjacent said opening through which it is adapted to be 40 removed when disconnected from the water receiving means and header.

2. A magazine heater having a casing; front and rear headers; a fuel magazine within the casing extending between the 45 headers and provided at its lower end with a water jacketed hopper; two water drums above the magazine; a detachable connection between each side of the interior of the upper part of the jacket and the interior of the 50 drum above such side; detachable connections between the interior of the lower part of the jacket and a header; and an opening through the casing and front header, the hopper having one end thereof adjacent said opening through which it is adapted to be removed when disconnected from the drums and header.

3. A magazine heater having a casing; front and rear headers; a fuel magazine 60 within the casing and extending between the headers; a water jacketed hopper extending between the headers beneath the said magazine, said hopper being detachably secured to the front header; water receiving means 65 above the magazine; detachable connections

between the interior of the upper part of the jacket of the hopper and the interior of said means; detachable connections between the interior of the lower part of the jacket and the interior of the rear header; and an opening through the casing and front header, the hopper having one end thereof adjacent said opening through which it is adapted to be removed when disconnected from the water receiving means and header.

4. A magazine heater having a casing; front and rear headers; pipes communicating between the headers and forming a fuel magazine; a water jacketed hopper extending between the headers beneath the said magazine; water receiving means above the magazine; detachable connections between the interior of the upper part of the jacket of the hopper and the interior of said means; detachable connections between the interior of the lower part of the jacket and the interior of a header; and an opening through the casing and front header, the hopper having one end thereof adjacent said opening through which it is adapted to be removed when disconnected from the water receiving means and header.

5. A magazine heater having a casing; front and rear headers; a fuel opening; a fuel magazine within the casing and extending between the headers; a water jacketed hopper extending between the headers beneath the said magazine; water receiving means above the magazine; detachable connections between the interior of the upper part of the jacket of the hopper and the interior of said means accessible through the fuel opening; detachable connections between the interior of the lower part of the jacket and the interior of a header; and an opening through the casing and front header, below the fuel opening, the hopper having one end thereof adjacent said opening through which it is adapted to be removed when disconnected from the water receiving means and header.

6. A magazine heater having a casing; front and rear headers; a fuel opening passing through the front header; a fuel magazine within the casing and extending between the headers; a water jacketed hopper extending between the headers beneath the said magazine, said hopper being detachably secured to the front header adjacent the fuel opening; water receiving means above the magazine; detachable connections between the interior of the upper part of the jacket of the hopper and the interior of said means accessible through the fuel opening; detachable connections between the interior of the lower part of the jacket and the interior of a header; and an opening through the casing and front header, below the fuel opening, the hopper having one end thereof adjacent said opening through which it is

adapted to be removed when disconnected from the water receiving means and headers.

7. A magazine heater having front and rear water headers, the rear header having a 5 thimble passing therethrough; front and rear smoke boxes enclosing the headers; water receiving means; a fuel magazine within the casing and extending between the headers; a water jacketed hopper extending 10 between the headers and having a detachable pipe connections with the water receiving means; detachable connections between the interior of the lower part of the jacket and the interior of the rear header, 15 said connections being located in the rear smoke box and being accessible therethrough; and an opening through the front header and smoke box, the hopper having one end thereof adjacent said opening 20 through which it is adapted to be removed when disconnected from the water receiving means and header.

8. A magazine heater having a water circulating system including front and rear 25 headers, the front header having an opening therethrough; a grate extending between the said headers; a fuel magazine located above the grate and extending the full length from front to rear thereof and including a hopper having a water jacketed 30 end and sides; detachable connections between the hopper and the said water system to provide circulation through the hopper, the hopper being adapted to be removed 35 through the said opening when disconnected from the water system and having its water jacketed end located adjacent the opening and sloped inwardly to permit the insertion of fuel through the said opening.

40 9. A magazine heater having a water circulating system including front and rear headers; an inverted V-shaped grate extending between the said headers; a fuel maga-

zine located above the grate and extending the full length from front to rear thereof 45 and including a hopper having a water jacketed end and sides; detachable connections between the hopper and the said water system to provide circulation through the hopper, the hopper being adapted to be removed through the said opening when disconnected from the water system and having its water jacketed end located adjacent the opening and sloped inwardly to permit the insertion of fuel through the said opening, the said sloping end being cut away at 50 a predetermined distance above the bottom of the hopper sides to allow fuel to flow to the front end of the apex of the grate when the hopper is in use. 55

10. A magazine heater including front and rear headers; a grate extending between the said headers; a fuel magazine located above the grate and extending the full length from front to rear thereof and including a hopper comprising a water jacketed end and sides; detachable connections whereby the hopper may be connected with a water system to provide circulation through the hopper, the front header having an opening therethrough above the top of the hopper for inserting fuel into the fuel magazine and having a second opening 70 therethrough below the first mentioned opening, the hopper being adapted to be removed through the second opening when disconnected from the water system and having its end adjacent the second opening sloped inwardly to permit the insertion of fuel through the said second opening. 75
